DESIGN FOR A DRIVING EXTENSION FOR POWER DRIVEN TOOL UNITS

Albert C. Koett, Cincinnati, Ohio, assignor to The Kett Tool Company, Cincinnati, Ohio

Application March 4, 1942, Serial No. 106,076

Term of patent 14 years

To all whom it may concern:

Be it known that I, Albert C. Koett, a citizen of the United States, residing at Cincinnati, in the county of Hamilton and State of Ohio, have invented a new, original, and ornamental Design for a Driving Extension for Power Driven Tool Units, of which the following is a specification, reference being had to the accompanying drawing, forming a part thereof.

The figure is a perspective view of the driving extension for power driven tool units, illustrating my new design. The design will appear the same if viewed from either side.

I claim:

The ornamental design for a driving extension for power driven tool units, substantially as shown and described.

ALBERT C. KOETT.
